C. E. HULL

SPARK BREAKER

Filed Oct. 17, 1922

Fig. 3.

Attorney

UNITED STATES PATENT OFFICE.

CHARLES E. HULL, OF ONAWAY, MICHIGAN.

SPARK BREAKER.

Application filed October 17, 1922. Serial No. 595,115.

To all whom it may concern:

Be it known that I, CHARLES E. HULL, a citizen of the United States, residing at Onaway, in the county of Presque Isle, 5 State of Michigan, have invented a new and useful Spark Breaker; and I do hereby declare the following to be a full, clear, and exact description of the invention, such as will enable others skilled in the art to which

10 it appertains to make and use the same.

The invention relates to spark breakers for locomotive smoke stacks and has for its object to provide a device of this character comprising a ball bearing supported ring 15 carried by a hinged member attached to the upper end of the stack and provided with a centrally disposed downwardly extending fan disposed within the stack and adapted to be rotated with the ring when gases are forced out of the stack. Also to provide the ball bearing supporting ring with a screen which revolves therewith and closes the stack opening, and a second screen carried by the hinged member disposed above the 20 ring carried screen, said screens allowing passage of gas for preventing sparks from passing out of the stack, the fan breaking the sparks during its rotation.

25 A further object is to provide one side of the stack with a removable receptacle, which receptacle receives cinders from the stack through an opening therein, incident to the rotation of the fan.

With the above and other objects in view 30 the invention resides in the combination and arrangement of parts as hereinafter set forth, shown in the drawing, described and claimed, it being understood that changes in the precise embodiment of the invention 35 may be made within the scope of what is claimed without departing from the spirit of the invention.

In the drawing:—

Figure 1 is a side elevation of a portion 45 of a stack, showing the device applied thereto and partly in section to better show the structure.

Figure 2 is a vertical transverse sectional view through the stack taken on line 2—2 50 of Figure 1.

Figure 3 is a top plan view of the stack, part being broken away to better show the structure.

Referring to the drawing, the numeral 1 55 designates a conventional form of locomotive stack through which gases are dis-

charged. Secured to the upper end of the stack is an annular member 2, to which is hingedly connected at 3, a fan carrying frame 4. The frame 4, when open allows 60 free access to the interior of the stack 1, however when closed, it is preferably held in closed position by means of the bolts 5. The upper side of the frame 4 is provided with an upwardly extending annular flange 65 6, on which is secured a convexed screen 7, for preventing passage of sparks from the stack 1, but allowing the passage of gases to the atmosphere. Rotatably mounted in an annular channel 8 of the frame 4, and on 70 ball bearings 9 is a fan carrying ring 10, which ring during its rotation supports the spark breaking fan 11 and gives momentum to the fan as it is rotated by the gases being forced upwardly through the stack 1. The 75 fan 11 is secured at 12 to a vertically disposed shaft 13, which shaft is rotatably mounted in a cross bar 14 carried by the frame 4, and has its upper end secured in a cross bar 15 carried by the bearing ring 10, 80 therefore it will be seen that the bearing ring 10 will revolve on the ball bearing 9 when the fan 11 is rotated by the forcing of gases through the stack 1, and consequently the 85 sparks will be broken up by the fan as it rotates. Secured to the upper side of the bearing ring 10 is a second screen 16, which is spaced from the under side of the screen 7, and freely rotates thereunder. Screen 16 90 also prevents passage of cinders from the 90 smoke stack.

During the rotation of the fan 11, the 95 sparks are churned adjacent the upper end of the stack 1 and the centrifugal force maintains the same in substantial engagement with the periphery of the stack 1. After the sparks have been thoroughly churned and broken up the fan forces the same through the opening 17 in the side wall of the stack 1, and downwardly through the 100 sleeve 18 into the removable receptacle 19, which receptacle has a bayonet slot connection 20 with the sleeve 18. The receptacle 19 may be removed when desired and accumulated cinders therein dumped.

105 From the above it will be seen that a spark breaker is provided, which is ball bearing supported by a bearing ring and in such a manner whereby the bearing ring will add momentum during the rotation of 110 the fan thereby lending force to the spark breaking action. It will also be seen that

the frame 4 when raised upwardly at its free end will raise the fan 11 and allow free access to the stack.

The invention having been set forth what is claimed as new and useful is:—

- 5 1. The combination with a smoke stack, of a spark breaker therefor, said spark breaker comprising an annular member secured to the upper end of the stack, an annular frame hingedly connected to one side of the annular member and registering therewith, a bearing ring disposed within the annular frame, said bearing ring being supported on anti frictional bearings, a 10 downwardly extending fan carried by the bearing ring and axially disposed within the upper end of the stack, an upwardly extending annular flange carried by the annular frame, a screen carried by the upper side of 15 the annular flange and registering with the stack opening and a screen carried by the upper side of the bearing ring and registering with the stack opening.
- 20 2. The combination with a smoke stack, of a spark arrester carried thereby, said spark arrester comprising an annular frame

hingedly connected to the upper end of the stack, a downwardly extending spark breaking fan, an annular bearing ring rotatably mounted on anti frictional bearings carried by the annular frame, said fan being disposed within the upper end of the stack and supported and connected to the annular bearing ring.

3. The combination with a smoke stack, 35 of a spark arrester and breaker therefor, said spark arrester and breaker comprising an annular frame hingedly connected to the upper end of the stack, a screen carried by the upper side of said frame, a rotatable 40 bearing ring carried by the annular frame, a spark breaking fan disposed within the upper end of the stack and connected to the bearing ring and a screen carried by the upper side of the bearing ring. 45

In testimony whereof I have signed my name to this specification in the presence of two subscribing witnesses.

CHARLES E. HULL.
